UNITED STATES PATENT OFFICE.

ARCHIBALD L. BROWN, OF CHICAGO, ILLINOIS.

ILLUMINATED SIGN.

SPECIFICATION forming part of Letters Patent No. 769,249, dated September 6, 1904.

Application filed June 11, 1902. Serial No. 111,101. (No model.)

To all whom it may concern:

Be it known that I, ARCHIBALD L. BROWN, a citizen of the United States, residing in Chicago, in the county of Cook and State of Illinois, have invented a new and useful Improvement 5 in Illuminated Signs, of which the following is a specification.

This invention relates to an improved construction of illuminated sign for drug-stores. 10 It is made in the form of and represents a druggist's mortar and is intended to render the sign much more striking and attractive in appearance than any heretofore constructed.

The invention consists in the novel features 15 hereinafter described.

In the accompanying drawings, Figure 1 is an elevation of the invention, and Fig. 2 a vertical section thereof. Figs. 3 and 4 are sections on the lines 3 3 and 4 4, respectively, 20 of Fig. 2. Fig. 5 is a section showing the manner of securing the jewels in the center band. Fig. 6 is a perspective of the lead frame employed for holding the opalescent glass. Fig. 7 is a perspective of the metal 25 rings or frames employed at top and bottom.

In said drawings, 8 represents a rod for supporting the sign, one end of the rod being attached customarily to the building and the other end being held up by a chain 9.

The sign is provided with a series of vertical 30 interior ribs 10, by which its parts are held together, and two of these ribs, located at opposite sides of the sign, are extended above the sign and bent over the rod 8, as plainly 35 shown.

The body of the sign is composed of a top band composed of curved sections of lettered glass, an inverted conical portion composed of leaded opalescent glass, a central metal 40 band studded with jewels, a second conical portion of leaded opalescent glass, and a bottom band composed of curved sections of lettered glass, all held together by the ribs 10. These several parts are individually constructed as 45 set forth below. The top lettered band consists of curved sections 11, of plain-surfaced glass, adapted to receive the letters 12 and to show such letters plainly both at day and night.

These glass sections are confined at top and 50 bottom between metal rings 13 and 14, both

properly secured to the ribs. The outside of the rings may be stamped in any ornamental pattern desired, and I have shown them as beaded. Both rings have internal flanges 15, between which and exterior rings 16 the glass 55 sections may be held against any inward or outward movement. The rings 16 are each preferably soldered to the main ring against which they abut. The bottom lettered band is very similar in construction to the upper 60 one, being composed of curved sections of glass 17, having letters 18, the sections being confined at top and bottom between rings 19 and 20 and between inner flanges 21, attached to said rings, and outer rings 22, soldered to 65 rings 19 and 20. All these parts correspond both in form and function to the like parts in the top band. Between the top and bottom lettered bands are conical opalescent glass sections 23 and 24 and the central jewel-studded 70 metal band 25. The band 25 is considerably less in diameter than the lettered bands, and the sections 23 and 24 consequently taper from the lettered bands to the band 25, though the sides are also curved or bowed inward, as 75 plainly shown. The sections 23 and 24 both consist of small sheets or panes 26, of colored glass, generally known to the trade as "opal- 80 escent" glass, and lead framing in which the panes are set in a manner well understood in the art. The lead framing is shown at Fig. 6. The central band is preferably shaped as shown, being bulged out along its central zone, so that a vertical section of the band describes a curve. In this band, which is made of metal, 85 I form numerous openings and fill the openings by means of colored jewels 28, held in place by rings 29 surrounding the jewels and frictionally engaging the openings.

The ribs 10 are preferably four in number, 90 and they are bent to conform to the interior of sections 23 and 24, and they may be soldered to the lead framing thereof, if desired. It is also desirable to attach to the rings 14 and 19 and also to the center band 25 rings 95 30, 31, 32, and 33, as shown, setting over the edges of the opalescent-glass sections. These rings are all soldered in place to the adjacent metal part of the sign.

The sign is illuminated in any suitable way— 100

as, for instance, by the incandescent lamps 34, supported on a board 35 and connected to the source of electricity by wire 36. A cover 37, of sheet metal, is provided, whereby rain may be excluded from the sign. The imitation pestle 38 is attached to the cover, and the ribs which attach the sign to the supporting-rod pass through the cover; but otherwise there is no opening in the latter except that for the 10 cowl-covered ventilator 39.

The bottom of the sign is formed of glass panes and metal framework, a portion 40 of the panes being associated in a frame 41 to form a door hinged at 42 42 and provided with 15 a catch 43. Outside the door is a surrounding metal casing 44 and other panes, 45, and their leadwork 46. The bottom may be supported within the hollow interior of the bottom ring 20.

20 The sign presents a very attractive appearance by daylight, but at night it is both striking and attractive and the whole body and outline of the mortar are clearly defined. It permits the use of different colors in the glass 25 and different combinations of colors. Handsome effects are produced in using ruby colors in the lettered glass, dark colors in jewels of the center band, and light colors in the conical sections. The opalescent glass heightens 30 the beauty of the sign by radiating the rays from the lamps in angling directions both up and down.

I claim—

35 1. The illuminated sign made in the form of a druggist's mortar and consisting of top and bottom lettered bands of glass, intermediate conical portions of leaded glass consisting of horizontal flanged rings and ribs connecting said rings, a studded central metal 40 band, means for uniting the bands and conical portions, and interior means for illuminating, substantially as specified.

45 2. The illuminated sign made in the form of a druggist's mortar and consisting of a top lettered band of glass and metal, an inverted conical portion composed of leaded opalescent glass, a central metal band studded with jewels, a second conical portion of leaded opalescent glass, said conical portions comprising 50 horizontal flanged rings, a bottom band of glass and metal, means for uniting said bands and conical portions consisting of ribs connecting said rings, and interior means for illuminating, substantially as specified.

55 3. The illuminated sign in the form of a druggist's mortar, having its body made of leaded stained glass and a central annular band of metal, the interior of said body being unobstructed, and combined with interior illuminating devices extended down to the bottom of the sign, substantially as specified.

4. The illuminated sign consisting of the lower conical section and the inverted upper conical section formed of separate pieces of 60 glass and metal framework, the central band of

metal interposed between said sections, suspending devices extending from above the upper section within and through the sign, and illuminating means within the sign, substantially as set forth.

70 5. The illuminated sign in the form of a druggist's mortar in which are combined curved glass sections 11 of substantially conical form and horizontally-arranged metal rings above and below the outwardly-extending 75 bases of such conical glass sections, means connecting said rings, and interior illuminating means, substantially as set forth.

6. The illuminated sign in the form of a druggist's mortar in which are combined curved glass sections 11 and metal rings above and below the glass sections and provided with vertical flanges inside the sections, and rings outside the sections serving to hold them against the flanges, substantially as 80 specified.

85 7. The illuminated druggist's sign having the form of a mortar, and provided with a band consisting of a series of bent lettered glass sections arranged around the vertical 90 axis of the sign to form a cylinder, and also provided with interior illuminating devices, substantially as specified.

8. The illuminated circular sign in which are combined leaded glass sections and horizontally-arranged metal rings above, below and between such sections, and ribs 95 connecting said rings, substantially as specified.

9. An illuminated sign having the form of a mortar, comprising two conical sections 100 arranged with their smaller ends toward each other forming an interior space, each section being composed of a frame having bendable flanges and separate panes of glass held by said flanges, flanged rings supporting the 105 conical sections at their ends, ribs connecting said rings with each other, and illuminating means in said space, substantially as set forth.

10. An illuminated sign having the form of a mortar, comprising two conical sections 110 arranged with their smaller ends toward each other, each section being composed of a frame having bendable flanges and separate panes of glass held by said flanges, a central metal band arranged between said conical sections, 115 means for uniting the ends of said sections and band, and illuminating means within the sign, substantially as set forth.

11. An illuminated sign having the form of a mortar, comprising two conical sections 120 arranged with their smaller ends toward each other and forming an interior space, said sections being composed of separate panes of glass, horizontal rings supporting the ends of said sections, vertically-arranged ribs 10 125 curved to correspond with the contour of said sections and secured to the horizontal rings, and illuminating means in said space, substantially as set forth.

12. The illuminated sign consisting of the 130

lower conical section and the upper inverted conical section arranged with their smaller ends toward each other, and formed of separate pieces of glass and metal framework, illuminating means within the sign, and suspending devices extending from above the upper section within and through the sign to the

bottom edge of the lower section, substantially as set forth.
